UNITED STATES PATENT OFFICE.

ALBERT FRY, OF EVANS, COLORADO.

ROAD-DRAG.

1,212,134.

Specification of Letters Patent.

Patented Jan. 9, 1917.

Application filed August 8, 1916. Serial No. 113,762.

To all whom it may concern:

Be it known that I, ALBERT FRY, a citizen of the United States, residing at Evans, in the county of Weld and State of Colorado, have invented certain new and useful Improvements in Road-Drags, of which the following is a specification.

This invention relates to road drags or graders and has special reference to the type of grader disclosed in Letters-Patent No. 1,175,430, granted to me March 14, 1916.

The particular object of the present improvements is to provide means whereby the scraper blades may be adjusted vertically with a finer degree of adjustment than in my previous machine and also to arrange the adjusting mechanism so that it will occupy less space.

The invention is illustrated in the accompanying drawings and will be hereinafter first fully described and then more particularly pointed out in the claims.

In the drawings, Figure 1 is a perspective view of the novel mechanism detached from the supporting frame or truck; Fig. 2 is a plan view of the complete grader; Fig. 3 is a side elevation of the same, parts being broken away; Fig. 4 is a detail perspective view of one of the brakes.

The truck or supporting frame consists of a bed 1 which is carried by wheels 2 and to which draft is applied in the usual manner. Scraper blades 3 are disposed below the truck and are connected with the front and rear axles by chains 4 and 6, respectively, in the manner fully set forth in my aforesaid patent. Two blades are employed and they are connected so as to be held in fixed parallel relation by brackets 6, clevis bars 7 being secured to the rear side of each blade and extending forwardly therefrom to be connected with the front chain 4 so that the blades will be readily drawn over the ground.

The truck 1 is braced by suitable cross bars and upon the central cross bar 8, I pivotally mount a supporting bar or beam 9 from the ends of which the scraper blades are suspended. The supporting beam 9 is mounted to swing in a horizontal plane and is secured in its angular position by a wing nut 10 mounted upon the upper end of the pivot bolt so as to bear upon the upper side of the beam, as will be readily understood. Upon the front side of the beam 9, at the ends of the same, I secure pulleys 11 over

which pass the flexible blade suspending and adjusting members 12. The said members will have their rear ends secured to the ends of the beam and pass downwardly therefrom under the pulleys 13, after which they pass up to and over the pulleys 11, as clearly shown. The chains or cables 14 are secured to the front and rear blades and converge upwardly therefrom to be secured to the blocks containing the pulleys 13 so that the blades will be thereby supported from the beam.

The members 12 extend forwardly from the pulleys 11 to the winding drums 15 which are mounted upon the standards 16, near the front end of the truck 1, the members being wrapped around the said drums so as to be unwound therefrom or wound thereon accordingly as it is desired to lower or raise the blades. The shafts of the winding drums are extended inwardly beyond the standard 16 and upon the inner ends of said shafts, I secure hand wheels 17 which may be easily operated by the driver from the seat 18 provided on the truck. The hand wheels are normally held against rotation by brakes which consist of leaf springs or resilient plates 19 having their forward ends secured upon the truck and their rear ends free and turned laterally to provide pedals 20 which may be easily depressed by the feet of the driver. Upon the upper sides of the springs I secure the brake shoes or blocks 21 which are disposed so as to normally bear upon the peripheries of the respective hand wheels, a pad or covering 22 of some friction-creating material being secured on the upper side of each block.

The chains 4 and 5 are adjusted so as to secure the blades at any desired angular relation to the line of draft and will hold them in said relation against side draft. The hand wheels 17 may be independently manipulated and one member 12 permitted to unwind while the other winds or remains at rest so that they will accommodate themselves to the angular adjustment of the blades. When it is desired, however, to raise or lower the blades, the hand wheels 105 must be simultaneously rotated in the same direction so that the vertical lengths of the cables will be shortened or increased, as will be readily understood. By unwinding one member and winding the other while allowing the chains 4 and 5 to remain undisturbed, the blades can be adjusted vertically

so as to conform to the arch of the road and impart any desired dip to the same.

It will be readily noted that my present arrangement permits the blades to be adjusted more finely in a vertical plane and that the same occupies less space upon the truck than that formerly employed. The brakes will permit any desired movement of the hand wheels if their free ends be depressed and will arrest the movement instantly if the pressure thereon be released.

Having thus described the invention, what is claimed as new is:

1. In a road grader, the combination of a truck, a supporting beam pivotally mounted for movement in a horizontal plane, pulleys secured upon said beam at the ends thereof, flexible members secured to the ends of the beam and passing over said pulleys, other pulleys mounted upon the said members between the first-mentioned pulleys and the points of attachment of the members to the beam, a blade suspended from the last-mentioned pulleys, and means at the front end of the truck for winding or unwinding the flexible members.

2. In a road grader, the combination of a truck, standards erected thereon near the front end of the same, a supporting beam pivoted on the frame for movement parallel

with the truck, guide pulleys on said beam, other pulleys below the beam, a blade disposed below the pulleys below the beam, connections between said pulleys and the blades, winding drums mounted upon said standards, flexible members secured to said drums and passing over the pulleys on the beam and under the pulleys connected with the blade and having their ends secured to the beam, and means for rotating the winding drums.

3. In a road grader, the combination of a truck, standards erected thereon near the front end of the same, a beam pivotally mounted on the truck for movement in a horizontal plane, winding drums mounted on said standards, hand wheels connected with the respective drums, brakes yieldably engaging said hand wheels, pulleys secured on the beam at the ends of the same, flexible members secured at their front ends to the winding drums and passing over the said pulleys and having their rear ends secured to the beam, pulleys mounted upon said flexible members between their rear ends and the pulleys on the beam, and a blade suspended from the last-mentioned pulleys.

In testimony whereof I affix my signature.

ALBERT FRY. [L.S.]
